MATERIAL HANDLING MECHANISM

Paul H. Voth, Cleveland, Ohio, assignor to Willard Storage Battery Company, Cleveland, Ohio, a corporation of West Virginia

Application December 6, 1941, Serial No. 421,928

7 Claims. (Cl. 15—93)

This invention relates to material handling and conveying mechanism and particularly to an improved form of take-out mechanism for transferring articles, particularly flat articles such as storage battery plates, from a substantially horizontal conveyor to suitable receiving means, such as a second conveyor, extending at substantially right angles to the first conveyor and with the articles supported thereon in substantially vertical position and in parallel relation one to another.

In certain respects this invention is an improvement on the subject matter of an application filed January 11, 1939, in the name of Alfred R. Willard, Serial No. 250,393, now Patent No. 2,266,110, granted December 16, 1941, and in certain other respects is an improvement on the construction shown in the E. W. Smith Patent No. 2,006,844 granted January 2, 1935.

The principal object of the present invention is to provide certain improvements in the constructions shown in the Willard and in the Smith patents above mentioned so as to provide a material handling apparatus and particularly a take-out mechanism which is generally more satisfactory in operation than the take-out mechanisms illustrated in said patents.

The invention may be briefly summarized as consisting in certain novel details of construction and combinations and arrangements of parts which will be described in the specification and set forth in the appended claims.

In the accompanying sheets of drawings showing the preferred embodiment of the invention:

Fig. 1 is an end view of the apparatus looking toward the take-out mechanism and the take-out or receiving conveyor;

Fig. 2 is a top plan view of the same partly in section substantially along the line 2—2 of Fig. 1;

Fig. 3 is a side view of the same;

Fig. 4 is an enlarged view partly in section showing the take-out mechanism in side elevation;

Fig. 5 is a detail sectional view substantially along the line 5—5 of Fig. 4;

Fig. 6 is a detail sectional view substantially along the line 6—6 of Fig. 4;

Fig. 7 is a view similar to Fig. 4 with certain parts for actuating the take-out mechanism shown in a different position than in Fig. 4;

Fig. 8 is a fragmentary sectional view substantially along the line 8—8 of Fig. 9;

Fig. 9 is an enlarged sectional plan view of the principal parts of the mechanism, the section being taken substantially along the line 2—2 of

Fig. 1, this view being similar to Fig. 2 but showing the parts on an enlarged scale;

Fig. 10 is a sectional plan view showing particularly the power unit, the section being taken substantially along the line 10—10 of Fig. 1;

Fig. 11 is a detail sectional view of part of the power unit, the section being taken substantially along the line 11—11 of Fig. 10; and

Fig. 12 is a detail sectional view substantially along the line 12—12 of Fig. 11.

The mechanism constituting the subject matter of this application, like the mechanisms of the Willard and the Smith patents referred to above, is designed particularly for conveying and handling double storage battery plates having corner lugs at their opposite ends, the plates being conveyed either directly from the pasting machine to the take-out mechanism or in some instances after they leave the pasting machine being first conveyed through a heating chamber which at least partially dries and sets the paste.

In the construction illustrated in the Willard patent, the take-out mechanism is in the form of an intermittently operated double star wheel which lifts the plates from the conveyor along which the plates travel from the pasting machine in horizontal position and delivers them in substantially vertical position onto receiving rails from which they are moved by intermittently operated pusher members onto an intermittently operated take-out conveyor, the plates being supported on the rails and on the take-out conveyor by their corner lugs with the body portions of the plates extending down between the rails and between the chains of the take-out conveyor.

In the Smith patent there is a combined take-out and transfer mechanism consisting of pairs of toothed sprocket chains which not only lift the plates off the intake conveyor and carry them through an arc of 90° from horizontal position to vertical position but part of the chains are continued beyond this point so as to support them in vertical position while they are being conveyed a substantial distance from the take-out point.

The present invention resides principally in an improved take-out mechanism, there being employed in place of the double star wheel of the Willard patent and instead of the pairs or groups of take-out and conveying chains of the Smith patent a take-out mechanism which consists of a pair of toothed wheels which engage under the inner edges of the plates and a pair of sprocket chains having teeth which engage under the outer edges of the plates. The toothed wheels

and toothed sprocket chains support the plates only while they are being moved through an arc of substantially 90°, i. e., while being transferred from horizontal position to substantially vertical position, and then the plates are automatically deposited onto the receiving means consisting in this instance of the intermittently moving chains of a take-out conveyor.

The articles handled by the present mechanism are in this instance double storage battery plates 15 with corner lugs 15a at their opposite ends. They are delivered to the take-out mechanism horizontally and in end-to-end relation by a chain conveyor which in this instance is in two sections including a main section 16 and a short auxiliary section 17 which is in line with section 16 and is located at the point where the plates 15 are lifted and swung upwardly by the take-out mechanism and delivered to the receiving mechanism. The chains of the two conveyor sections 16 and 17 are driven continuously and at the same speed, and in the gap between the two sections 16 and 17 driven rollers 18 are provided to insure the uninterrupted delivery of the plates from the section 16 to the section 17.

All the parts of the mechanism constituting the present invention, with the exception of the far end of the conveyor section 16 and the far end of the take-out conveyor to be referred to presently are supported by a frame which is designated as a whole by the reference character 19, and when the various parts of the mechanism are referred to it may be assumed that they are supported by the frame 19.

In the lower part of the frame is a power unit to be referred to presently, and this power unit drives the chains of the conveyor sections 16 and 17 continuously and actuates intermittently the take-out mechanism and other parts to be referred to. This power unit, through chain and sprocket gearing 20 including a sprocket on the conveyor shaft 21, drives the chains of the conveyor section 16 and the chains of the conveyor section 17 are driven from shaft 21 by chain and sprocket gearing 22. The chains of the conveyor sections 16 and 17 engage suitable sprockets on sprocket supporting shafts which need not be described in detail.

The plates are stopped on the auxiliary section 17 of the conveyor in position to be picked up by the take-out mechanism and the mechanism for stopping the plates is like that disclosed in the Willard patent and, briefly, is as follows: Near the end of the travel of each plate 15 it engages a finger 23 mounted on an arm 24 journaled to swing on a vertical stud 25 and the movement of the plate 15 is stopped when the arm 24 engages an adjustable stop 26 shown in dotted lines in Fig. 9. The swinging movement imparted to the arm 24 operates a switch 27 which causes the energization of a solenoid which will be referred to presently and which controls the intermittent movements of certain of the parts including the take-out mechanism which will now be described. Just before the plates engage the finger 23 their movement is retarded by having their forward side edges frictionally engage flexible retarders. These retarders in this instance consist of flexible sheet metal fingers 23a supported on a U-shaped frame 23b. These fingers have portions projecting upwardly from the forward ends of the arms of the frame 23b, note particularly Fig. 8, and at their upper ends have outwardly flared projecting portions arranged so as to be engaged

by the forward side edges of the plates and in a position so as not to interfere with the toothed members of the take-out mechanism.

The take-out mechanism consists of two lifting and supporting members for the inner portions of the plates 15, these being in the form of two toothed wheels 28 (see Figs. 1, 4, 7, and 9) and two lifting and supporting members for the outer portions of the plates 15, these being in the form of two sprocket chains 29, the latter having plate engaging teeth or lugs 30 (see Figs. 1, 3, 4, 5, 6, and 7). The wheels 28 which have equally spaced peripheral plate engaging teeth are secured on a horizontal shaft 31 which is supported by the frame on the inner side of the auxiliary conveyor 17 and at about the level of the latter. The chains 29 pass around two end sprockets 32 secured to a lower horizontal shaft 33 and around two end sprockets 34 secured to an upper horizontal shaft 35. The shaft 33 extends along the outer side of the auxiliary conveyor 17 at the level of the shaft 31 and the upper shaft 35 is a suitable distance above the shaft 31. The outer runs of the chains 29 engage idler sprockets 36 and the inner runs of the chains engage arc-shaped guides 37 having chain engaging arc-shaped slots (see particularly Figs. 5 and 6) which are concentric with the axis of shaft 31 and therefore concentric with respect to the plate lifting and supporting toothed wheels 28. The idler sprockets are adjustably supported on extensions of the guides (see Figs. 4 and 7).

The wheels 28 and the chains 29 are moved intermittently and the number of teeth on the wheels and chains and the extent of movement imparted to the wheels and chains are such that at each intermittent movement both the wheels and the lower runs of the chains 29 are moved an arcuate or angular distance equal to the spacing of the teeth on the wheels 28 and the spacing of the teeth 30 on the inner arc-shaped runs of the chains 29, note particularly Fig. 4. When a plate 15 comes to rest on the auxiliary conveyor section 17, a pair of teeth on the wheels 28 and a pair of teeth on the arcuate portions of the chains 29 are directed beneath the inner and outer edges respectively of the plate on the auxiliary conveyor 17, and as soon as the plate comes to rest the wheels 28 and the chains 29 lift and advance the plate a distance equal to the arcuate or angular distance between the teeth, as explained above. The plates 15 gradually approach upright position and when they reach substantially upright position they leave the wheels 28 and chains 29 of the take-out mechanism and drop by gravity onto an intermittently operated receiving conveyor 38 consisting of two chains supported by rails 39 of the frame 19, the lugs 15a of the plates resting on the chains and the body portions of the plates extending down between the chains. The plates are moved along this conveyor in spaced relation as shown in Fig. 4 with their lower edges engaging a bar 40 adjustable as to height, the purpose of this bar being to prevent the plates from swinging and damaging one another as they are deposited by the take-out mechanism onto the chains of the receiving conveyor 38. It is to be noted particularly by reference to Figs. 1 and 4 that the forward sprockets which support the chains of the receiving conveyor 38 are located between the shaft 31 supporting the lower toothed wheels 28 and the upper shaft 35 which supports the sprockets 34 engaged by the toothed chains 29. In other words, the receiving

conveyor 38 projects well in between the shafts 31 and 35 so that when the plates reach substantially vertical position and are discharged by the take-out mechanism they drop by gravity onto horizontal portions of the upper runs of the chains of the receiving conveyor 38. This arrangement does not interfere with the step-by-step movement of the plates from horizontal to substantially vertical position since the forwardly or inwardly projecting ends of the conveyor 38 are on opposite sides of the body portions of the plates, it being remembered that when the plates pass onto the conveyor 38 the corner lugs 15a of the plates engage the chains of the conveyor with the body portions of the plates extending down between the chains.

As in the Willard patent, a wiper mechanism is employed to clean the forward edges of the plates of excess paste as they are lifted off the auxiliary conveyor by the take-out mechanism. This wiper mechanism includes a fixed wiper blade 41, an intermittently reciprocating cleaner blade 42 beneath the wiper blade 41 and at its forward edge engaging the lower side of the front portion of the wiper blade 41, and a fixed blade 43 the front edge of which is adapted to engage the under side of the reciprocating cleaner blade 42. As fully explained in the Willard patent, the cleaner blade 42 cleans off the paste adhering to the front edge portion of the wiper blade 41 after each wiping operation by the blade 41, and as the blade 42 moves back and forth between the front portions of the blades 41 and 43 its forward edge is cleared of paste. Although the arrangement and functioning of the blades are as in the Willard patent, the cleaner blade 42 is reciprocated by improved means which will be described shortly.

The power unit is in the main similar to that of the Willard patent but has been improved and simplified by the elimination of one cam on the intermittently rotated shaft to be referred to. The power unit is supported in the lower part of the frame and includes a motor 44 which through spur gearing 45 drives a shaft of reduction gearing in a gear case 46 from which extends a constantly rotating main drive shaft 47. Through bevel gearing 48 this shaft 47 drives a conveyor drive shaft 49 which drives continuously the chain and sprocket gearing 20 which in turn continuously drives the chains 16 and 17.

In line with shaft 47 is an intermittently actuated shaft 50 which is adapted to be clutched to shaft 47 through the medium of a clutch 51 which when engaged makes one revolution and is then automatically disengaged. The clutch shown in Figs. 10, 11, and 12 includes a constantly rotating driving clutch member 52 keyed or otherwise secured to shaft 47 and an intermittently rotated driven clutch member 53 which is secured to an intermittently rotated shaft 50. The driving member 52 has secured to it a disk 55 with closely spaced radial slots 56 while the driven member 53 carries a pivoted dog 57 which is spring-pressed inwardly and when permitted so to do engages in one of the slots 56 so as to form the driving engagement between the clutch members. The engagement and disengagement of the clutch are controlled by a cam member 58 which normally lies closely adjacent to the slotted face of the driving disk 55 in position to cam the dog 57 out of one of the slots 56. The cam member 58 is carried by a pivoted arm 59 which

is normally held in the position shown in Fig. 11 by a spring 60 but is adapted to be momentarily shifted from that position so as to allow the clutch to engage by a link 61 connected to the plunger of a solenoid 62 shown conventionally in Figs. 10 and 11.

This solenoid is adapted to be momentarily energized by the switch 27 which is actuated by each plate as it reaches the end of its forward movement on the auxiliary conveyor 17. When the solenoid is energized it retracts cam 58 allowing the dog 57 to drop into one of the slots 56 of disk 55, and when the driven clutch member 53 has made one revolution, the clutch is disengaged by reason of the fact that the cam 58 cams the dog 57 from the slot 56, the solenoid meanwhile having been deenergized. Intermittently driven shaft 50 is preferably provided with a suitable brake indicated at 63 to prevent the driven clutch member and shaft 50 from overrunning. Various types of brakes may be employed, but in this instance the brake is of the friction disk type.

During each intermittent revolution of shaft 50 intermittent movements are imparted to the toothed wheels 28 and the toothed sprocket chains 29 of the take-out mechanism, to the chains of the receiving conveyor 38, and to the reciprocating cleaner blade 42. To accomplish this, the shaft 50 is provided with two cams 64 and 65 which are engaged by rollers 66 carried by levers 67 and 68 which are normally biased downward by coil springs 69 with the corresponding rollers engaging the peripheries of the cams.

One of the levers 67 is connected by a link 10 to an arm 71 fixed to a horizontal shaft 72. This shaft has secured to it a second arm 73 which is connected by a rod 74 attached at its upper end to an arm 75 mounted to swing on a shaft 76 and carrying a pawl 77 engaging the teeth of a ratchet wheel 78 which is secured to the shaft 76, this shaft having a pair of sprockets which are engaged by the chains of the receiving conveyor 38. Thus each time the solenoid 62 is energized, causing the temporary engagement of the clutch 51, the chains of the receiving conveyor 38 are given one of their intermittent movements sufficient in extent to advance the desired distance the plates 15 which have already been deposited on the chains by the take-out mechanism.

Connected to the free end of lever 68 is an upstanding arm 79 which at its upper end is connected to an arm 80 carrying a pawl 81 which engages the teeth of a ratchet wheel 82 secured to the upper horizontal shaft 35 to which is secured the upper pair of sprockets 34 which are engaged by the two pairs of sprocket chains 29, see particularly Figs. 1 and 4. These sprocket wheels 34 are thus moved intermittently in a clockwise direction as the same are viewed in Figs. 1, 4, and 7, and they are held by a suitable spring pawl 83 from turning in the reverse direction on the down stroke of the arm 80 with its actuating pawl 81. The arm 80 is in the nature of a bell crank and has a second arm 84 provided at its free end with a roller 85 engaging in a slot 86 of an arm 87 having at its lower end a hub 88 mounted for oscillatory movement on the lower shaft 31 carrying the toothed wheels 28. This arm 87 carries a pawl 89 which engages the teeth of a ratchet wheel 90 fixed to the shaft 31. Each time that the arm 80 is swung upward there is given to the ratchet wheel 82 and to the upper sprocket wheels

engaged by the sprocket chains 29 a sufficient angular movement in a clockwise direction as viewed in Figs. 1, 4, and 7 to impart the desired increment of movement to the chains 29. At the same time a lateral movement is given to the roller 85 to swing the arm 87 a sufficient distance to cause the pawl 89 and the ratchet wheel 90 to turn the toothed wheels 28 a sufficient distance (in a counterclockwise direction as viewed in Figs. 1, 4, and 7) to impart to the toothed wheels 28 the same angular or arcuate movement that is imparted to the upper sprocket wheels 34 and the inner runs of the chains 37.

It will be noted particularly by reference to Figs. 4 and 7 that the lower part of the slot 86 at the upper end of arm 87 is substantially radial and that the upper part is at an angle to the lower part. Consequently the angular or rocking movement imparted by the roller to arm 87 is initially more rapid than the latter part, in fact the angular arrangement of the lower and upper portions of the slot 86 may be such that the entire angular movement which is imparted to the arm 87 during each cycle of the take-out mechanism may occur while the roller is traveling through the lower radial portion of the slot. Obviously the linear distance between the teeth 30 of the sprocket chains 29 is greater than the linear distance between the peripheral teeth of the toothed wheels 28 and the outer portions of the plates 15 are of course moved a greater linear distance than the inner portions during each cycle of the take-out mechanism. However, by shaping the slots 86 as illustrated and described above, the initial movement and in fact the entire movement of the toothed wheels 28 may be such that the teeth at the peripheries of the toothed wheels 28 move as rapidly as the teeth on the inner runs of the sprocket chains 29 but for a shorter space of time, and this action or result is preferred. Accordingly, when the plates 15 are initially lifted off the auxiliary conveyor 17, they are lifted vertically, i. e., are maintained horizontal until the arcuate movement of the toothed wheels 28 is completed after which the movement of the sprocket chains continues until their increment of movement is completed during which time the plate is tilted as indicated in Figs. 4 and 7, i. e., is given its increment of arcuate movement. A further advantage of this method of operation is the fact that there is less whipping action imparted to the plates 15 and therefore less likelihood of dislodgment of the paste from the grids. On the return stroke of the arm 79 and of the arms 80 and 84, the arm 87 is swung from the position shown in Fig. 4 to the position shown in Fig. 7, and at such time the toothed wheels 28 and the ratchet 90 are held against turning in the reverse direction by a spring finger 91 which engages the ratchet. Not only do the cam 65 and the mechanism above described cause the intermittent movements to be imparted to the toothed wheels 28 and the sprocket chains 29, but they also cause in each cycle of movement of the take-out mechanism and in predetermined timed relation with respect to the movements imparted to the toothed wheels 28 and the chains 29 the forward and return movements of the cleaner blade 42. This is accomplished by the following mechanism.

Slidably mounted on the arm 87 is a slide 92 which at its upper end is provided with a hook 93 which is so arranged that during the upward movement of the roller 85 it engages this hook

and moves the slide 92 upward from the position shown in Figs. 1 and 4 to the position shown in Fig. 7 a distance determined by the length of a slot 94 which is engaged by a pin carried by the arm 87. Secured to one side of the slide 92 is an arm 95 the lower end of which is bent laterally and is engaged by a roller 96 carried by one arm of a bell crank 97 journaled on a pin 98. The other arm of the bell crank is connected by a sliding pin 99 to the reciprocating cleaner blade 42. Thus during each intermittent actuation of the toothed wheels 28 and the sprocket chains 29 the cleaner blade 42 is moved forwardly in proper timed relation with the movements of the wheels 28 and the chains 29 and is then retracted by the action of a spring 100 which assists gravity in restoring the slide 92 to its lowermost position on the arm 87.

To adapt the machine for storage battery plates of different lengths, the switch 27 including the finger 23, the swinging arm 24, the adjustable stop 26, the retarder 23a, and the wiper mechanism including the support for the bell crank 97 can be adjusted as a unit as all these parts are mounted upon a slide 101 which can be moved back and forth lengthwise of the conveyor sections 16 and 17 by turning a shaft 102 (see Figs. 8 and 9). A change in the length of the plates requires a change in the space between the chains of the receiving conveyor 38 and this adjustment can be made by shafts and bevel gearing designated as a whole by the reference character 103 and adapted to be turned by a shaft which may be provided at its outer end with a crank 104 (see Figs. 1 and 3). Additionally, the parts supported by the slide 101 not only can be adjusted as a unit but they are also independently adjustable. For example, the switch 27, the arm 24, and the adjustable stop 26 are mounted on a support 105 adjustably secured to the slide 101. The plate retarders 23a including the frame 23b are carried by a support 106 and the blades of the wiper mechanism and the bell crank 97 are carried by a support 107 both of which supports are also adjustably secured to the slide 101. However, no invention is claimed in these features per se as they are fully described in the Willard patent as is also mechanism for stopping the operation of the machine if plates pile up immediately in advance of the auxiliary conveyor 17, this being accomplished by switch controlling mechanism shown partly at 108 in Fig. 9.

While I have shown the preferred construction, I do not desire to be confined to the precise details illustrated and described but aim in my claims to cover all modifications which do not involve a departure from the spirit and the scope of the invention.

Having thus described my invention, I claim:

1. In combination with a substantially horizontal conveyor for conveying articles and receiving means extending at substantially right angles to the conveyor, a take-out mechanism for transferring the articles from the conveyor to the receiving means, said take-out mechanism including a pair of wheels having peripheral teeth for engaging under the inner edges of the articles, a pair of chains having teeth for engaging under the outer edges of the articles, a pair of lower sprocket wheels and a pair of upper sprocket wheels about which the chains pass and guides for maintaining the inner runs of the chains in arcs of circles concentric with respect to the toothed wheels, said pair of first-named wheels

being spaced from and located substantially horizontally opposite the pair of lower sprocket wheels and being spaced from and located substantially vertically below said pair of upper sprocket wheels, and said receiving means being independent of said pairs of wheels and chains and having its inner end adjacent to said wheels and to the outer ends of the chains in position such that when the articles being transferred by the take-out mechanism from the conveyor to the receiving means reach substantially vertical position they pass onto the inner end of the receiving means.

2. A take-out mechanism for transferring articles from a substantially horizontal conveyor to receiving means, said take-out mechanism including a pair of wheels having peripheral teeth for engaging under the inner edges of the articles, a pair of chains having teeth for engaging under the outer edges of the articles, guides for maintaining the inner runs of the chains in arcs of circles concentric with respect to the toothed wheels, and means for intermittently actuating the toothed wheels and chains, said means including a rocking part for actuating the chains and means operated by said part for actuating the toothed wheels, said receiving means being independent of said wheels and chains and having its inner end located adjacent to said wheels and the outer ends of said chains.

3. A take-out mechanism for transferring articles from a substantially horizontal conveyor to receiving means, said take-out mechanism including a pair of wheels having peripheral teeth for engaging under the inner edges of the articles, a pair of chains having teeth for engaging under the outer edges of the articles, guides for maintaining the inner runs of the chains in arcs of circles concentric with respect to the toothed wheels, and means for intermittently actuating the toothed wheels and chains, said means comprising a rocking part for actuating the chains and a second rocking part for actuating the toothed wheels, one of said parts having a slot and the other having a projection extending into the slot.

4. In combination, a take-out mechanism for transferring articles from a substantially horizontal conveyor to receiving means, said take-out mechanism including a pair of wheels having peripheral teeth for engaging under the inner edges of the articles, a pair of chains having teeth for engaging under the outer edges of the articles and guides for maintaining the inner runs of the chains in arcs of circles concentric with respect to the toothed wheels, and means for actuating said take-out mechanism including an intermittently operated power shaft having an actuating cam thereon and mechanism operated by said cam for actuating both the chains and the toothed wheels.

5. In combination with a substantially horizontal conveyor for conveying flat articles and receiving means located above and extending at substantially right angles to the conveyor, a take-out mechanism for transferring the articles from the conveyor to the receiving means with the articles delivered thereto in substantially vertical position, said take-out mechanism including toothed members for engaging under the inner edges of the articles and toothed members for engaging under the outer edges of the articles, and mechanism including means for simultaneously imparting equal arcuate movements to said inner and outer toothed members with the inner toothed members moved at least initially as fast as the outer toothed members during each cycle of movement.

6. In combination with a substantially horizontal conveyor for conveying flat articles and receiving means located above and extending at substantially right angles to the conveyor, a take-out mechanism for transferring the articles from the conveyor to the receiving means with the articles delivered thereto in substantially vertical position, said take-out mechanism including toothed members for engaging under the inner edges of the articles and toothed members for engaging under the outer edges of the articles, and mechanism for giving intermittent movements to said inner and outer toothed members including means for causing said inner toothed members and outer toothed members to be actuated at the same time but with the angular movement of the inner toothed members completed prior to the angular movement of the outer toothed members.

7. In combination with a substantially horizontal conveyor for conveying flat articles such as storage battery plates and receiving means extending above and at substantially right angles to the conveyor, a take-out mechanism for transferring the articles from the conveyor to the receiving means and for delivering the same to the latter in substantially vertical position, said take-out mechanism including toothed members for engaging under the inner edges of the articles and toothed members for engaging under the outer edges of the articles, a wiper mechanism for wiping edges of the articles as they are moved by the take-out mechanism including a reciprocating blade and mechanism for giving said take-out mechanism and blade intermittent movements including an intermittently operated power driven shaft with a power transmitting member thereon, and means operatively connecting said power transmitting member to the inner toothed members, to the outer toothed members, and to said reciprocating blade.

PAUL H. VOTH.
